BENJAMIN F. WILSON, OF GEDDES, NEW YORK.

Letters Patent No. 88,932, dated April 13, 1869.

IMPROVEMENT IN SASH-HOLDER.

The Schedule referred to in these Letters Patent and making part of the same.

To whom it may concern:

Be it known that I, BENJAMIN F. WILSON, of Geddes, in the county of Onondaga, in the State of New York, have invented a new and improved Mode of Supporting and Locking Window-Sashes; and I do hereby declare that the following is a full and exact description thereof, reference being had to the accompanying drawings, and to the letters of reference marked thereon.

The nature of my invention consists in the use of a ball, or wheel, in combination with a double, fixed inclined plane, for the purpose of supporting a window-sash in any required position, or locking the same, when closed.

To enable others skilled in the art to make and use my invention, I will proceed to describe its construction and operation.

Figure 1 is a front view of the case, made of iron, or other suitable material, with the inclined planes A A and wheel B shown in dotted lines, slots G G, retaining-notch E, and semicircular notch F, the wheel being made of hard wood, rubber, iron, or part iron, and part rubber, or any other suitable material.

Figure 2. B shows the wheel detached from the case, provided with a knob, D, and shank C.

The knob of the wheel is for the purpose of operating the wheel from the outside of the case, fig. 1, through slots G G.

The notch E, fig. 1, is for the purpose of retaining the wheel B in an inoperative position, so that the sash may be moved freely up or down.

They can be made without the retaining-notch, and

the sash will never, through inadvertence, be left unlocked.

The semicircular notch F, fig. 1, is provided, so that the wheel B, shank C, and knob D, (fig. 2,) can be made in one piece, and be readily placed in position in the case, thus greatly facilitating the manufacture.

The inclined planes can be formed in the sash itself, in which case, only the front plate of the wheel-case will be required, or the case can be made in a form suitable to be mortised into the sash.

The operation is as follows:

The case with wheel inserted being attached to the sash in proper position, and the wheel B, by means of knob D, placed, with shank C, in the retaining-notch E, the sash can be placed in the required position, when, by pushing the wheel up, it will become wedged between the inclined plane and the side of the window-frame, and support the sash; on slightly raising the sash, the wheel will be released, and drop to the lower inclined plane, when, on lowering the sash, it will be locked down, without further attention.

Figure 3 shows the sash, locked down.

Figures 4 and 5 show the same, supported.

I claim—

The retaining-notch E and semicircular notch F, in combination with the knob D, shank C, wheel B, double inclines A A, and inclined slots G G, all arranged to operate substantially as herein shown and described.

Witnesses: BENJAMIN F. WILSON.
